BRUSH AND CRUMBER SET

Filed Aug. 28, 1945

2 Sheets-Sheet 2

INVENTOR.
FOSTER F. MONACO

BY
James C. Ledbetter
ATTORNEY.

brush seat 7 is in the plane of the lower surface of the slot, that is, flush therewith, and thus forms an inward continuation of the slot.

An ear, in the form of a back-rest 8, is carried on the outside of the rear rim 3 in alignment with the centrally disposed slot 5 and inner brush seat 7. It will be noted that the upper surface of the back-rest 8 is in the same plane and forms a continuation of the upper surface of the seat 7 and of the lower surface of the slot 5. Thus the top surfaces of the slot 5 and seat 7 as well as the back-rest 8 are flush and form one continuous supporting shelf or rest area for the brush, as later explained.

A brush handle 10 may have a hole in its outer end by which to hang up the device when it is not in service. The handle 10 may be larger at its outer end and may taper inwardly to a narrower straight-side shank portion 11. The inner end of the narrow or restricted handle shank 11 joins a bristle-holding body 12 carrying brush bristles 13 secured in the body in any known manner. The body 12 of the brush is somewhat narrower laterally than the tray 2, and likewise the length of the bristle portion 13 with the brush body 12 is less than the length of the tray. This relation is shown in Fig. 3, and such arrangement is made in order that the bristles 13 of the brush may be carried entirely within the tray and protected thereby. It is observed that the free ends of the bristles 13 are well within the tray 2 and inside the open pick-up front side edge 4.

A pair of wings 14 are formed symmetrically on the brush handle shank 11 where it joins the bristle body 12. Each wing 14 is shown on the outer edge of the brush handle shank 11 and (as shown in Fig. 7) is flush with the bottom surface of the handle 10, 11. The spread of the two wings 14 (one on each side of the handle shank 11), including the width of the adjacent portion of the handle between said wings, has an area comparable to that of the open T-space 5, 6 (Fig. 8) of the tray and also of the back-rest 8.

In other words, the thickness and width of the wing pair 14 is about equal to the open area of the tray slot 5 and the supporting area of the back-rest 8. And the brush handle 10, 11 is thicker than the wing pair 14, thus adapting the handle to lie between the spaced lugs 6, while the wings lie within the tray slot 5 and under the retainer lugs 6.

The width of the handle shank portion 11, which is adjacent and between the wings 14, is restricted or slightly narrower than the clearance space between the overhanging retaining lugs 6 of the tray. And the outer end of the handle may be shaped somewhat larger as, for example, by tapering it as shown in the drawings and previously explained.

It will be seen that the brush 10, 12 may be interconnected with the tray 2 by placing the reduced-size handle shank 11 (see Figs. 1 and 2) through the clearance space or entry 5, 6 (Fig. 8) formed by the two spaced retaining lugs 6, and thereupon the brush handle 10, 11 is shifted or displaced outwardly away from the rear side of the tray, until the handle wings or enlarged portion 14 slide into the slot 5 (see Fig. 3). This arrangement disengageably connects the tray 2 and brush 12 together, locates the brush bristles 13 wholly within the tray body 2 for protection, and extends the handle 10, 11 outside the tray. Accordingly, the two-part assembled device can be carried by simply holding the brush handle 10.

To separate the brush 12 from the tray 2, these

two parts are simply shifted from Fig. 3 position to that indicated in Fig. 1, whereupon the brush handle 10, 11 is lifted by rectilinear movement from between the retaining lugs 6. The slip-in wing pair 14 of the brush handle, together with the T-spaced slot 5, 6 of the tray, provide a simple assembly means by which the two parts of the brush crumber device are assembled when not in service.

10 The combined taper 10 and straight shank 11 of the handle means provide the narrow or restricted handle portion 11 adjacent the wing pair 14 by which to insert the handle through the clearance space 5 defined by the retaining lugs 6, and at the same time provide an enlarged handle outer end portion 10 for convenience in holding the brush in one hand for sweeping debris into the tray held in the other hand.

15 It is seen that the tapering enlargement of the handle 10, extending outwardly from the straight-side shank 11, prevents the brush from sliding too far inwardly in relation to the tray. In other words, the tapered handle enlargement 10 or other equivalent means, provides a stop against 20 the outside back of the tray rim 3 at the slot 5, after the brush is pushed forwardly (toward the pick-up edge 4) sufficiently to disengage the handle wings 14 from the slot 5 by which to lift the brush out of the tray. This arrangement prevents the brush from sliding into the tray, and also means that the brush handle can only be inserted into the tray by perpendicular movement through the spaced retaining lugs 6.

25 The inner or lower restricted-size shank end 11 of the brush handle 10, with its wing pair 14, rest upon the protruding ear-like back-rest 8 for support. Thus the back-rest 8, with the cooperating lugs 6, stabilizes or steadies the brush in the tray and conversely the tray on the brush. The flush formation of the upper surfaces of the back-rest 8 and shouldered seat 7 provides a long bearing surface and guide to support and retain the brush handle 11 where it extends through the flange 3 of the tray.

30 It will be noted that the upper straight edge portion of the brush body may rest against the straight shoulder or seat 7 and that the bottom surface of the brush body 12 lies flat against the bottom 2 of the tray. This makes a neat compact assembly when the two parts are placed together as a unit and hung on a peg when not in use.

35 When the tray and brush are interconnected, for example when hung out of the way by placing the device on a peg through the hole in the handle 10, it will be noted that the weight of the tray maintains its seat 7 downwardly against the upper edge of the body 12 of the brush. Accordingly, the T-slot 5, 6 of the tray and the slip-in wings 50 14 of the brush handle need not necessarily be a close or sliding fit in order that the two parts remain together as a unit.

40 In manufacturing this brush and crumber set, it is found that molded plastic affords one suitable material, that contrasting colors may be used for the two parts, and that the device readily may be decorated by filigreeing the production molds.

45 The disclosure herein explains the principle of the invention and presents the best mode contemplated in applying such principle, so as to distinguish the invention from others; and there is particularly pointed out and claimed, the part, improvement or combination, which constitutes the invention or discovery, as understood by a comparison thereof with the prior art.

This invention is presented to fill the need for a useful brush and crumber set. Various modifications in construction, mode of operation, use and method, may and often do occur to others skilled in the art, especially so after acquaintance with an invention. Accordingly, this disclosure is exemplary of the principles and equivalents without being limited to the present showing of the invention.

What is claimed is:

A brush and crumber set comprising, in combination, a tray and a brush, the tray having an upstanding rim which is provided with a slot therethrough, an ear in the form of a back-rest extending outwardly from the slot in alignment with one surface of the slot to leave said slot open through the rim, a pair of lugs carried on the rim, one lug at each side of the slot and overhanging said slot, thus providing an entry clearance into the slot; a handle formed on the brush, made with a shank portion narrower than the entry clearance between the pair of lugs on the tray rim, and made with a wing on each side of the shank, the two wings and shank being wider than the entry clearance but conforming in size to the slot; whereby the brush handle is adapted to have its shank portion inserted into the entry clearance, and shifted so as to bring the two wings within

the slot and into position onto the back-rest for detachably connecting the handle and tray together.
